UNITED STATES PATENT OFFICE.

HEZEKIAH B. WYSONG AND WILLIAM H. WYSONG, OF NORTH MANCHESTER, INDIANA.

MOLASSES EVAPORATOR, FILTER, COOLER, AND FURNACE.

SPECIFICATION forming part of Letters Patent No. 236,867, dated January 18, 1881.

Application filed July 17, 1880. (No model.)

To all whom it may concern:

Be it known that we, HEZEKIAH B. WYSONG and WILLIAM H. WYSONG, of North Manchester, in the county of Wabash and State of Indiana, have invented a new and valuable Improvement in Molasses Evaporators, Filters, Coolers, and Furnaces; and we do hereby declare that the following is a full, clear, and exact description of the construction and operation of the same, reference being had to the annexed drawings, making a part of this specification, and to the letters and figures of reference marked thereon.

Figure 1 of the drawings is a representation 15 of a plan view of my improved machine. Fig. 2 is a longitudinal section thereof. Fig. 3 is a vertical sectional view of the cooler, and Figs. 4 and 5 are details.

This invention has relation to improvements 20 in apparatus for filtering, boiling, and cooling maple-sap, sugar-cane juices, and the like, for the purpose of making molasses, sirup, and sugar.

The nature of the invention will be fully set 25 forth hereinafter.

In the annexed drawings, the letter A designates the furnace, built of masonry, and of suitable length, and having in one end the fire-box *a* and at the other a stack, *b*. The 30 products of combustion pass through the throat *c* of the fire-box and into a flue, *d*, formed by a horizontal partition, *f*, of the masonry, the upward extension *g* of the side walls thereof, and the bottom of the evaporator B, into the 35 stack through a duct, *d'*, leading into the same. Below the partition *f* is a second flue, *h*, leading to the open bottom of the stack, and provided with two dampers, *k* and *l*, arranged on crank-shafts *m n*, and capable of being thrown 40 up across the flue, thus directing the products of combustion into the flue *h*, away from the bottom of the evaporator, when the heat becomes too great.

The evaporator is composed of a metallic 45 pan of suitable depth, divided by transverse partitions *o o'* into a number of boiling-pans, C C' C'', and a molasses-pan, D. The partitions *o* are provided with vertically-sliding gates *p*, that open or cut off communication 50 between the pans, and which are raised or low-

ered by the levers *q*, fulcrumed on the edge of the evaporator. The boiling-pan C has a lateral extension, D', reaching out beyond the furnace-walls, and terminating in an inclined or curved end wall, *r*, outside of which is a 55 scum-receptacle, E.

The boiling-pans C C' C'' and pan D are arranged relative to the fire-box as follows: The pan C is directly over it, pan C' comes next to pan C, pan C'' next, and pan D terminates 60 at the stack, being farthest from the fire-box. This pan D has no communication with pan C'', the partition *o'* having no gate, and during boiling is filled with water to prevent its being burned out. Extending around the pans 65 C C' C'' and the extension D' of the former are the lateral troughs F G, communicating respectively with the pans C and C'' by means of the ducts *s*, leading from them into the same, and closed by suitable valves. As shown in 70 Fig. 2, the damper *k* cuts off the heat when thrown up from the pans C' C'' and D, leaving the pan C exposed to it, while the damper *l* simply protects the molasses-pan D.

The cane-juice is delivered from a filtering 75 or straining tank, G', into the side trough, F, whence it passes into the pans C C' C'', where it is boiled until it becomes a sirup of sufficient thickness. During the boiling the scum rises and overflows into the side troughs, F G, 80 and passes into the pan C, whence it is received in the extension D'. Becoming cool, the scum is raked or drawn up the curved or inclined end *r* of said extension and deposited in the receptacle E. The charge being thoroughly skimmed, the water is let out of pan D and the contents of pan C'' transferred thereto by means of a suitable dipper. This pan being emptied, the contents of the next pan is let into it by raising its gate, and in like 85 manner transferred to the pan D, and so on until all the pans are emptied. The pans C C' C'' may now receive a fresh charge of juice, while the contents of pan D are being reduced to the desired consistency. This being accomplished, the molasses is drawn off through a cock, *t*, falls into a conduit, *a'*, and is carried to the cooler H. This is composed essentially of a number of horizontally-arranged hopper-shaped trays, I, having a perforation, *u*, in their 90 100

bottoms, and arranged the one above the other in a suitable frame, J. Between the trays are arranged the conical spreaders K. The molasses in the upper tray flows through its 5 perforation *u* onto the conical apex of the spreader below, and is carried thereby in an outward direction. Falling over its rim, it is received by the next tray, and, being directed inward, passes through it onto the next spreader, and so on to the bottom tray. The devi-
ous course taken by the molasses causes it to part rapidly with its caloric, so that on reaching the last tray it is ready for use or for conversion into sugar.

15 The filterer or strainer is composed of a tank, K', usually supported upon a stand, and divided by the partitions *xz* into three compartments, L L' L''. The compartment L is the juice-receptacle, and it communicates with the 20 division L' by means of a slot, *r*, in the lower edge of the partition *x*. The partition *z* has near its upper edge a gauze-covered slot, *y*. The juice, on entering the division L', must rise to the slot *y* before it can pass into the division L'', 25 whence it is fed to the troughs F and G through a suitable faucet, and dirt, grit, and such heavy impurities are here precipitated, while pieces of cane, leaves, and the like are strained out at the gauze-covered opening aforesaid.

30 What I claim as new, and desire to secure by Letters Patent, is—

1. In a syrup or molasses machine, the combination of the furnace A, having the inde-

pendent horizontal flues *d h*, opening the one into the side and the other into the bottom of 35 the stack, the valved openings in the division-wall of said flues, and a mechanism operating the valves to disclose the openings and close the upper flue, with the evaporator B, seated on said furnace and having the horizontally- 40 arranged boiling-pans C C' C'' and molasses-pan D, substantially as specified.

2. The evaporator consisting of the juice-boiling pans C C' C'' and the molasses-boiling pan D, the lateral extension D', having the 45 curved or inclined end wall, *r*, and scum-receptacle E, and the lateral troughs F G, communicating respectively with the pans C C' C'' and extension D', substantially as and for the purposes set forth.

3. The combination, with a sap-evaporator, having pan C, extension D', and troughs F G, of a filterer or strainer consisting of the tank K', having division-walls *xz*, forming compartments L L' L'', the wall *x* having slot *r* at its 55 lower edge, and wall *z* a gauze-covered opening, *y*, near its upper edge, substantially as specified.

In testimony that we claim the above we have hereninto subscribed our names in the presence of two witnesses.

HEZEKIAH BENJAMIN WYSONG,

WILLIAM H. WYSONG.
